Attorneys.

UNITED STATES PATENT OFFICE.

EBENEZER H. BOOTH, OF BINGHAMTON, NEW YORK.

PIPE WRENCH.

Application filed February 13, 1923. Serial No. 618,816.

To all whom it may concern:

Be it known that I, EBENEZER H. BOOTH, a citizen of the United States, resident of Binghamton, in the county of Broome and State of New York, have made a certain new and useful Invention in Pipe Wrenches; and I declare the following to be a full, clear, and exact description of the same, such as will enable others skilled in the art to which it appertains to make and use the invention, reference being had to the accompanying drawings, and to letters or figures of reference marked thereon, which form a part of this specification.

Figure 1 is a side view of the wrench with parts in work gripping position.

Figure 2 is a similar view with work released.

Figure 3 is a section on line 3—3, Figure 1.

Figure 4 is a fragmentary perspective view of the wrench.

The invention has relation to pipe wrenches, having for an object to provide an improved wrench of simple and durable nature, capable of quick adjustment, and of quick release without the use of springs. Other objects and advantages will appear.

The invention consists in the novel construction and combinations of parts, as hereinafter set forth.

In the accompanying drawings illustrating the invention, the numeral 1 designates the stationary jaw, having a shank or handle bar 2, forged in a single piece and provided near its head end with a recess 3 in its upper face, and made somewhat broader and thicker adjacent said recess.

Fitting within the recess 3 is the shank 4 of the fulcrum block 5, a transverse fulcrum pin 6, connecting said shank with the side walls or cheeks of the recess 3. The fulcrum piece is slotted longitudinally at 7 to receive the shank 8 of the movable jaw 9,

and slotted transversely at 10 to receive the nut 11, within which is threaded the shank 8 of the movable jaw.

In Figure 1 of the drawings, the wrench is shown engaged with the work 12, the fulcrum block being rocked upon its pin 6 forwardly, the tapered shank 4 of said block

contacting at its top or upper part forwardly at 13 with the forward wall of the recess 3 and at its lower part rearwardly at 14 with the rear wall of said recess, the 55 said contact points being substantially diametrically opposite the pin 6 to thereby fix the shank 4 of the fulcrum block rigidly in its recess 3 irrespective of the pin 6, to thereby relieve said pin of strain. There 60 is a further margin of movement of the movable jaw as it engages with the work, owing to forward rocking of the nut 11 within the transverse slot 10 of the fulcrum block. 65

The release of the wrench from the work is accomplished by finger pressure upon the tail end 15 of the shank of the movable jaw, thereby rocking the fulcrum block rearwardly upon the pin 6, as shown in 70 Figure 2, the end 15 of said shank being adapted to lie within reach of the thumb of the operator and for engagement by said thumb.

The rocking of the fulcrum block forwardly as stated in the engagement of the wrench with the work is automatic in the self adjustment of the movable jaw to the work. 75

The wrench is designed to do away with 80 the use of a spring or springs to release it from the work and to avoid the use of an outer yoke upon the main shank or handle bar. The fulcrum block 5 is laterally extended at 16 at each side of its tapered 85 shank 4, thereby overlying the broader portion 17 of the shank or bar 2 of the stationary jaw, the recess 3 being beveled laterally at its top at 18, and the head of the fulcrum block being beveled at its lower lateral portions at 19 to fit within the beveled portions 18, said beveled parts being adapted to contact at 20 in the forward rocking of the fulcrum block as in Figure 1, to further take the strain. 90

I claim:—

In a pipe wrench, a stationary jaw having a recess, a recessed rockable fulcrum block having a shank fitting within said recess, a nut located within the fulcrum 100 block, a movable jaw having a shank having threaded engagement with said nut, and

a fulcrum pin located centrally of said shank and pivotally connecting the same with the side walls of said recess centrally of the latter, said fulcrum block being rockable upon said pin and the shank of said block making contact with the end walls of said recess at points diametrically opposite said pin in the movement of said block in the

engagement of the wrench with the work to thereby relieve the pin of strain. 10

In testimony whereof I affix my signature in presence of two witnesses.

EBENEZER H. BOOTH.

Witnesses:

JESSE C. BOOTH,
LELIA BOOTH.
